UNITED STATES PATENT OFFICE.

HIRAM C. BLOOMINGDALE, OF NEW YORK, N. Y., ASSIGNOR TO CARD DISPLAY, INC., OF NEW YORK, N. Y., A CORPORATION OF NEW YORK.

SIGN.

Application filed July 28, 1926. Serial No. 125,366.

REISSUED

This invention relates to improvements in signs, and more particularly to price signs such as are used in department stores and other places.

5 Department stores require a large number of price signs because of the great variety of articles they handle and the different prices at which the various articles are sold. In the large stores this necessitates the employment of a force of skilled sign-makers who paint the signs by hand as required. By reason of the variation in the prices of the articles it is impractical to keep in stock a supply of printed price signs suitable for 10 all requirements. Because of the fact that the signs are now generally painted by hand they lack uniformity in appearance which gives a somewhat disagreeable impression on walking through the various departments of 15 the store.

My invention has for its object the provision of price signs that can be readily made up from uniform stock parts by unskilled persons. The invention enables a store to 20 keep the parts in a small space at a convenient point and to give them out to the various departments upon requisition where they can be made up by employees of the departments as needed.

30 While I have pointed out the advantages of my invention for large stores, it will be appreciated that it is equally advantageous for small stores and shops. It is also to be understood that the signs may be used for 35 other purposes than displaying prices.

In the accompanying drawings illustrating the invention:—

Figure 1 is a front view of one of my improved price signs;

40 Fig. 2 is a rear view thereof;

Fig. 3 is a section on the line 3—3 of Fig. 1;

Fig. 4 is a front view of one of the price cards detached from the frame;

45 Fig. 5 is a rear view of a modified frame member; and,

Fig. 6 is a modification of the price card.

Referring now to the drawings, the sign comprises a frame member 1 made of a flat 50 piece of card-board or other suitable material having its central portion cut away and removed to provide an opening 2, which opening is of suitable size and form to receive the cards 3. The cards 3 are each 55 printed or marked with a numeral, character,

or other desired indicia, and are so formed that they fit into the opening 2, but, preferably, with a slight space between adjacent cards, as indicated in Fig. 1. By making the combined width of the cards slightly less than the width of the opening 2, I find that the cards can be easily inserted in the opening of the frame and that the likelihood of their warping is minimized.

The frame 1 is provided with a marking 4 that surrounds the edge of the opening 2 and is of a color that contrasts with the color of the frame. For example, where a white frame is used I prefer to have the marking 4 black. I have found that the provision of this marking gives an optical effect which tends to conceal the spacing between the cards 3 that otherwise would be noticeable.

The cards 3 are all uniform in size and shape, and they may be arranged in any desired combination with respect to the markings contained thereon. If desired the frame and the cards may be of the same color, or they may be of different colors thus enabling the construction of a multi-colored sign.

In making up the sign, the cards 3 are adhesively fastened to the frame. For this purpose I prefer to use strips 5 of gummed paper such as is commonly used for binding packages and is available in most stores. Preferably the frame 1 is laid face down on a flat surface and the cards 3, also face down, are laid in the opening 2. Strips of the 85 gummed paper 5 are then applied over the upper and lower ends of the cards so as to secure the cards to the frame. If desired the strips 5 may first be pasted over the upper and lower edges of the opening 2 and 90 then the cards 3 can be pasted on to the exposed portions of the strips. After the sign has served its purpose, the cards 3 may be detached from the frame and the parts can be reused for another sign.

100 In the modification illustrated in Figs. 5 and 6, the back of the frame is provided with bands of adhesive 6 adjacent the upper and lower edges of the opening 2. In this instance the cards 3 are made somewhat longer than the space between the upper and lower edges of the opening so that they can be affixed at their ends to the bands of adhesive, which bands also serve to properly 105 locate the cards.

Various other modifications in the details of construction herein shown and described may be made without departing from the scope of the invention.

5 What I claim is:—

A sign including a body having an opening therein, a plurality of cards fitted in the opening and being disposed in relatively close side by side relation, said cards being each of a length so as to have their end

edges substantially abut the adjacent walls resultant from the opening and the outer side edges of the outer cards substantially abut the end walls resultant from the opening, and strip-like means adhesively secured to the back of the body and lapping the ends of each of the cards so as to simultaneously secure all of the cards to the body.
